The ornamental design for a milk receptacle of a breast pump, as shown and described.

DESCRIPTION

FIG. 1 is a front perspective view of a milk receptacle for a breast pump showing our new design.

FIG. 2 is a front elevation view thereof.

FIG. 3 is a rear view thereof.

FIG. 4 is a right side elevation view thereof.

FIG. 5 is a left side elevation view thereof.

FIG. 6 is a top plan view thereof; and,

FIG. 7 is a bottom plan view thereof.

The broken lines in the drawings depict portions of the milk receptacle for a breast pump that form no part of the claimed design. The dash-dot broken line defines the bounds of the claimed design and forms no part thereof.
